(57) CLAIM

The ornamental design for a wine skirt, as shown and described.

DESCRIPTION

FIG. 1 is a perspective view of the wine skirt showing our new design thereof;

FIG. 2 is a side view thereof;

FIG. 3 is a top view thereof; and,

FIG. 4 is a bottom perspective view thereof.

The glass shown in broken lines in the drawing views represents unclaimed portions of a wine skirt which are included for the purpose of illustrating unclaimed environment only, and forms no part of the claimed design.
